PIPE WRENCH

Samuel N. Hall, Tujunga, Calif.

Application January 27, 1937, Serial No. 122,594

1 Claim. (Cl. 81—70)

This invention relates to pipe wrenches of the type shown and described in United States Patent No. 1,320,615, issued to me November 4, 1919, and more particularly to pipe wrenches of the 5 chain type.

Among the salient objects of the present invention is to provide a pipe chain wrench which is in better alinement and better balance than those now on the market, thus making a wrench which 10 will not tend to twist downwardly so much when used on vertical pipe; to provide a wrench of the character referred to in which the chain is attached or anchored at a greater distance from the work engaging face of the jaws, thus causing 15 a better gripping effect of the jaws on the pipe; to provide in a wrench of the character referred to a longer connecting link between the sides of the wrench and pivotally connecting the end of the chain therewith, thus giving a greater 20 arc of engagement of the pipe along the operating jaws of the wrench; to secure the jaws in such a wrench with bolts which are at opposite sides of the pivotal connection of the connecting link for the chain, and in general, to provide an 25 improved pipe chain wrench which is more symmetrical and beautiful than the wrench in the patent referred to.

In order to more definitely explain my improved wrench, I have shown the same on the accompanying sheet of drawings which I will now describe.

Figure 1 is a side elevation of a wrench embodying my invention, showing it connected to a pipe in full lines for turning in one direction and 35 showing in light broken lines how the pivotal connection of the chain can be swung to reverse the direction of operation;

Figure 2 is an edge view of the wrench shown in Fig. 1;

Figures 3 and 4 are sectional views taken, respectively, on lines 3—3, and 4—4 of Fig. 2; with parts broken away to reduce the size of the view;

Figure 5 is a top plan view of the end of the handle disconnected; and

Figure 6 is a bottom plan view of the end of said handle.

Referring in detail to the drawing, 7 designates the handle, shown to be of round form and at its attached end being formed with two opposite flat faces, as 8, 8, and a reduced thickness portion 9, and the extreme end 10 of forked form, as at 11, the opposite sides of said forked portion terminating in holding toes 12, 12, for a purpose again referred to.

The jaws, 13, 13, are the same and are adapted

to fit upon the opposite sides of the end of said handle, and secured thereto by means of two bolts, 14, 14, at opposite ends of the reduced thickness portion 9, as will be clear from the drawing. The jaws are thus spaced laterally apart, as seen 5 in Fig. 2, and of symmetrical form with curved pipe engaging portions 13', 13', with their teeth pointing outwardly, and with rearward curved pipe engaging portions 15, 15, with their teeth pointing rearwardly, as shown in Fig. 1. 10

Pivots connected between the opposite sides of the reduced thickness portion 9, and the jaws, are two link members 16, 16, one end of said links being connected near the upper edge of the reduced handle portion, as at 17 and adapted to 15 swing forwardly or rearwardly between the bolts 14, 14, said links 16, 16, having secured between their outer ends a pipe chain 18, of the usual type and adapted to be placed around a pipe, or other round object, and to be brought up between the outer ends of the side jaws, in the manner indicated in Figs. 1, 2, 3 and 4, hooked over the holding toes 12, 12, the pivot pins of said chain being extended shortly beyond the side links making up the chain, in a known manner. 25

I have also shown an intermediate jaw member 19 secured to the underside of the end of the handle, between the side jaws 13, 13, as seen in Fig. 4, and secured to said handle end by means of a bolt or rivet 20, and a short stud 21 30 inserted into the meeting faces of the end of the handle and the intermediate jaw member 19, as indicated in Fig. 4.

The pipe is designated P and in Fig. 1 is shown with the wrench attached thereto in solid lines 35 for turning it clockwise. In this figure, in light broken lines, the links 16 are shown swung rearwardly and the pipe held against the jaws at 15, 15, in which position the engagement is such that the pipe can be turned in the opposite direction, as indicated by the small arrows within said pipe. 40

It will be noted that the jaw members 13, 13, are in straight and fixed alinement with the handle and that the length of the connecting 45 links 16, 16 for the chain and the clearance for their swing, makes it possible to adjust the wrench quickly to reverse the direction of operation on the pipe.

Attention is called to the fact that with the side 50 jaw members 13, 13, secured to the opposite sides of the handle, and at the reduced thickness portion thereof and in alinement therewith, there is provided spaces between said jaws and the opposite sides of said reduced thickness portion and 55

in these spaces, nearer the top edge of said reduced thickness portion of said handle, the chain connecting link is pivotally connected at its upper end. This gives a substantial overlap of the link members upon the opposite sides of said reduced thickness portion and also said intermediate jaws 19, so that there is no play or lateral movement of the free end of the link. This is an improvement over my other structures and makes for more satisfactory operation. It makes for a stronger connection also of the chain to the body of the wrench.

I do not limit the invention to the details of construction and arrangement shown, except as I may be limited by the hereto appended claim.

I claim:

A pipe wrench including a handle having its work end reduced in thickness and widened on

the side opposite from the work engaging edge, a pair of chain link members pivotally attached on the widened side of the reduced thickness of the handle whereby to give a longer swing to said chain members, a pair of jaw members bolted to opposite sides of said handle with two bolts at the opposite ends of said reduced portion of said body and through the thicker portions thereof, said jaw members being toothed at their rearward ends and at their forward ends and being symmetrical and longitudinally parallel with the length of said handle, whereby to give balance, a pipe embracing chain attached to the free end of said chain link members, and means on the end of the handle for detachably connecting the chain when placed around the work.

SAMUEL N. HALL.
